RICHARD C. LEAKE, OF ROCHESTER, NEW YORK, ASSIGNEE TO GENERAL RAILWAY SIGNAL COMPANY, OF GATES, NEW YORK, A CORPORATION OF NEW YORK.

AUTOMATIC TRAIN-CONTROL SYSTEM.

61,291,565.

Specification of Letters Patent. Patented Jan. 14, 1919.

Application filed July 23, 1915. Serial No. 41,524.

To all whom it may concern:

Be it known that I, RICHARD C. LEAKE, a citizen of the United States, and a resident of the city of Rochester, in the county of Monroe and State of New York, have invented a new and useful Automatic Train-Control System, of which the following is a specification:

This invention relates to systems for automatically controlling railway trains, and more particularly to such systems in which the movement of the train is controlled, in some appropriate way, by speed control apparatus and automatic stop mechanism carried on the train, the control of said speed control apparatus and said stop mechanism being accomplished mechanically and electrically by the co-operation of a contact shoe or similar device carried by the train and ramps or similar devices located along the trackway.

One of the principal objects of the invention is to devise an arrangement of circuits for controlling the ramps along the trackway so as to maintain these ramps in the same condition as a train passes them, whereby the operation and efficiency of the system will not be affected if more than one vehicle, as a locomotive or a motor car, equipped with the automatic train control apparatus is included in a train.

A further object of the invention is to devise a simple and reliable train control apparatus and ramps along the trackway, together with circuits and electrical connections therefor which will constitute adequate means for controlling the movement of the train both under conditions which require the train to proceed cautiously and under conditions which require the train to be brought to an absolute stop.

A further object of the invention is to devise an automatic system for controlling railway trains for a block system in which the information for the proper control of the trains may be transmitted from one block to another and which will require the least amount of apparatus and line wires between said blocks.

Other objects and advantages will appear as the description of the invention pro-

gresses, and the novel features of the invention will be particularly pointed out in the appended claims.

Generally stated, the invention consists in providing a short control section at the entrance to each block section of the trackway to which is connected and by which is controlled suitable electrical appliances so that the condition of the ramp or control device adjacent to each control section will be maintained the same while a train is passing that control section.

The invention further consists in providing a ramp for each block section of the trackway which is connected to suitable electrical appliances which are responsive to the presence of trains in certain of said block sections, and which will cause different electrical conditions to exist for each ramp according to the presence of trains on certain block sections; and in further providing suitable train control apparatus carried by the train which is responsive to the electrical conditions of said ramps.

The invention further consists in the parts and in the arrangements and combinations of parts, more fully set forth hereinafter.

In describing the invention in detail, reference is had to the accompanying drawing, wherein I have illustrated a preferred physical embodiment of my invention, and wherein like characters of reference designate corresponding parts throughout the several views, and in which:

The figure is a diagrammatic illustration of a railway train or vehicle and a track for said train, and shows the parts of an automatic train control system embodying the invention, both those parts which are associated with the train and those which are located along the track, together with circuits and electrical connections between said parts, the operative parts being shown in said figure in their normal positions and in the condition existing when a train is approaching one of the ramps and when traffic conditions permit said train to proceed at unrestricted speed.

Referring to the accompanying drawing, one track rail 1 of the railway track is electrically continuous, the separate rail sections

thereof being suitably bonded together; and the other track rail 2 is divided into electrically distinct sections A, B, C, D, and E in any suitable way, as by insulating joints 5. 3. The sections A, C and E may be of any length desired to obtain the required spacing of the trains, and for convenience in description will be hereinafter termed block sections. The sections B and D are comparatively short and may be as short as desired, providing that they are longer than the distance between any two successive pairs of wheels. In other words, the sections B and D, which will be hereinafter termed 10 control sections, are long enough so that as the train passes over them at least one pair of wheels of said train will at all times be on said control section. Although only two control sections B and D, the intermediate 15 block section C and the adjacent ends of the two block sections A and E are shown in the drawings, it is to be understood that the same alternate arrangement of control sections and block sections is carried out 20 throughout the desired length of the track, a control section being located at the entrance to each block section, as illustrated, the direction of normal traffic being indicated by the arrow X.

30 Extending along the track are two line wires 4 and 5, which are supported in any suitable manner, as on poles according to the usual construction; and these line wires 4 and 5 are electrically connected to a source 35 of alternating current, as a generator 6. The parts and the circuits are the same for the control sections B and D, and the parts and conductors associated with the control section D are given the same reference characters as the corresponding parts and conductors of the control section B with a distinctive exponent ¹ added thereto. Adjacent to one end of each block section is a track transformer 7, the secondary of which 45 is connected by wires 8 and 9 to the track rails 1 and 2 of said block sections. To the other end of each block section a track relay 10 is connected across the track rails 1 and 2, said track relay 10 being of any 50 suitable construction which will make said track relay responsive to alternating current. The track relays 10, together with the track rails 1 and 2 and the track transformers 7 of each block section constitute 55 the well known normally closed track circuit, as will be clearly understood by those skilled in the art of railway signaling. Normally, that is, when no train occupies a block section, the track relay 10 of that 60 block section is energized and the armatures 11, 12, 13 and 14 of said track relay will be in their upper position as shown in the drawing.

Associated with each control section is a 65 relay L, hereinafter termed a ramp relay.

The relay L is of the type commonly known in the art as a three-position alternating current relay, and is susceptible to alternating current, although immune to direct currents. This relay is illustrated according to established convention; and, as will be understood by those skilled in the art of alternating current railway signaling, comprises a rotor (not shown) which is operatively connected to the armatures 17, 18, 19 of the relay and which, when the two coils 15 and 16 of said relay are energized by alternating current, will move said armatures in one direction or the other from their neutral position, shown in the drawing, according to the way in which said coils 15 and 16 are energized. The detail construction of this three-position ramp relay is not shown and described, since this type of relay is well known in the art; and the features of the operation of this type of relay which are essential to a clear understanding of this invention, will be pointed out hereinafter in the description of the operation.

Adjacent to the entrance of each control section B and D is a contact rail or ramp R, which is supported in any suitable way, as on the ties by special supporting members, adjacent to one of the track rails; but said ramp R is insulated from said ties and from the track rails.

Associated with each control section B and D is a transformer 20 which is used as a source of electrical energy to create either a high or a low difference of potential between the corresponding ramp and the track rails. The primary of this transformer 20 is connected to the line wires 4 and 5 and its secondary is connected to conductors, hereinafter fully set forth, through the medium of which the above mentioned high and low conditions of potential are created. Also associated with each control section is another transformer 21, the primary of which is connected to the line wires 4 and 5 and the secondary of which is arranged to supply current to energize the coil 15 of the corresponding ramp relay L. Another transformer 22 is associated with each control section and is connected in a similar way to the line wires 4 and 5 and is used to supply current to the coil 16 of the ramp relay L associated with the preceding control section.

The conductors and electrical connections between the ramps and the armatures of the track relays 10 and ramp relays L will not be described in detail, since these conductors and the different operating circuits will be set forth fully hereinafter in the description of the operation.

The railway train is shown diagrammatically as comprising two pairs of wheels 24-24 connected by the usual axles 25 and 130

27, respectively, which pairs of wheels and axles may represent the wheels and axles of separate cars of a train. The axles 25 and 27 are illustrated as connected by a bar 28 which represents the frames of the cars constituting the train.

A supporting bar or bracket 30 is suitably supported on the train, preferably being fixed to one axle or journal box as shown; and supported on the bracket 30 is a vertically movable shoe or plunger 31 which is pressed downwardly by a compression spring 32. The shoe 31 is arranged to coöperate with the ramps R along the track-way as the train passes by said ramps and is designed so that when engaging one of said ramps it will be raised and interrupt a normally-closed circuit on the train for controlling the operation of the automatic train control apparatus. For this purpose the shoe 31 may operate any suitable form of circuit controlling device, but is shown as being provided with a button 33 of insulating material which is arranged to engage the underside of a contact spring 34 and to lift said contact spring out of contact with a contact member 35, when said shoe 31 is raised.

The mechanism carried by the train for controlling the movement thereof comprises a device S which is constructed and arranged so as to bring the train to a stop when said device is operated. Since this device S forms no part of this invention, and since various devices well known in the art are capable of performing its necessary functions, a detail description of the device S is deemed to be unnecessary. For instance, the device S may be an electro-pneumatic valve which can be operated to vent the train pipe of the well known pneumatic braking system and thereby cause an emergency application of the brakes and bring the train to a stop.

The mechanism for controlling the movement of the train also includes a device K which is constructed and arranged to control the movement of the train when the train should proceed cautiously. This device K, like the device S, forms no part of this invention and may be any one of the various devices well known in the art for accomplishing this purpose. The device K may be used to control automatically the speed of the train by causing an immediate application of the brake; or the device K may operate to apply the brakes at a point in the travel of the train determined from the speed of the train and the distance it has traveled after the device K was set into operation. For example, the device K may be a speed control apparatus such as shown and described in the patent to Paul J. Simmen, 1,150,809, dated August 17, 1915.

The stop device S is controlled by a direct

current stop relay S^a which has two armatures 36 and 37. The armature 37 of the stop relay S^a, when in its upper position, closes a circuit for energizing the device S to render it incapable of stopping the train, 70 said circuit being as follows:

Circuit number one.

Battery 38, conductors 39 and 40, armature 37 in its upper position, conductor 41, 75 device S and conductors 42 and 43 back to the battery 38.

The speed control device K is controlled by a direct current control relay K^a having two armatures 45 and 46. When the armature 46 of the control relay K^a is in its upper position it closes a circuit for supplying current to the device K to render it incapable of controlling the movement of the train, 80 said circuit being as follows:

Circuit number two.

Battery 38, conductors 39 and 47, armature 46 in its upper position, conductor 48, 90 device K, and conductors 49 and 43 back to the battery 38.

When the shoe 31 is in its lower normal position, as shown in the drawing, that is, when the shoe is not in engagement with a ramp, the stop relay S^a and the control relay K^a are normally energized from a local source of current carried by the train, as a battery 50. This normally closed direct current holding circuit for the stop relay S^a is as follows:

Circuit number three.

Battery 50, conductors 51 and 52, contact member 35, contact spring 34, conductors 53 and 54, armature 36 in its upper position, 105 conductors 55 and 56, stop relay S^a, and conductors 57 and 58 back to the battery 50.

The direct current holding circuit for the control relay K^a is as follows:

Circuit number four.

Battery 50, conductors 51 and 52, contact member 35, contact spring 34, conductors 53 and 59, armature 45 in its upper position, 115 conductors 60 and 61, control relay K^a, and conductors 62 and 58 back to the battery 50.

The energization of the stop relay S^a is also controlled by an armature 63 of the alternating current stop relay S^b, the stop relay S^b being energized when said armature 63 is in its upper position according to the following circuit:

Circuit number five.

Battery 50, conductors 51, 64 and 65, armature 63 in its upper position, conductors 66 and 56, stop relay S^b, and conductors 57 and 58 back to the battery 50.

In a similar way the control relay K^a is energized when the armature 67 of an alter-

nating current control relay K^a is in its upper position according to the following circuit:

Circuit number six.

- 5 Battery 50, conductors 51, 64 and 68, armature 67 in its upper position, conductors 69 and 61, control relay K^a , and conductors 62 and 58 back to the battery 50.
- 10 The alternating current stop relay S^a and the alternating current control relay K^a are arranged in parallel in a partial circuit including the shoe 31 and the frame 28 of the vehicle, this partial circuit for the alternating current stop relay S^a being as follows:
- 15

Circuit number seven.

- From the shoe 31, conductors 70 and 71, relay S^a , and conductors 72 and 73 to the
- 20 frame 28 of the train.

The partial circuit in multiple with the above-mentioned partial circuit for the alternating current control relay K^a is as follows:

25 *Circuit number eight.*

- From the shoe 31, conductors 70 and 74, relay K^a , and conductors 75 and 73, to the frame 28 of the vehicle.

- 30 The purpose of this partial circuit and the effect produced by supplying alternating current to it will be more fully described hereinafter in the description of the operation.

- 35 Having described generally the structure and arrangement of the various parts constituting the system for automatically controlling railway trains which embodies the invention, and in general the operation of
- 40 the parts of this system which are mounted on the train, the operation of the system as a whole will be described for different cases in which certain conditions of traffic, such as may occur in practice, are assumed to exist
- 45 along the trackway.

- For the first condition of traffic to be considered, assume that the train under consideration is in the block section A and is about to enter the control section B, as
- 50 shown in the drawing; that said train has found the trackway unobstructed and is running without being under the control of the speed control device K, and that neither the block section C or E are occupied by a train.
- 55 Since the block sections C and E are not occupied, their respective track relays 10 and 10¹ are energized and the armatures of said track relays are in their upper positions, as shown in the drawing. Before
- 60 the wheels of the train enter the control section B, the shoe 31 carried by said train engages the ramp R and in addition to making electrical contact with said ramp, said shoe is raised and presses the contact spring
- 65 34 out of contact with the contact member

35. At the time the shoe 31 engages the ramp R a high difference of potential exists between that ramp and the track rail 1 because of the normally closed partial circuit as follows:

70 *Circuit number nine.*

From the ramp R, conductor 80, armature 12 of the track relay 10 in its upper position, conductors 81 and 82 to the secondary of the

75 transformer 20, high voltage tap h and conductor 83 to the track rail 1.

Consequently, when the shoe 31 makes electrical contact with the ramp R, current is supplied to the alternating current relays 80 S^a and K^a , since the high difference of potential between the ramp R and the track rail, which is existent because of the partial circuit number nine, sends current through the partial circuits numbers seven and eight

85 for said relays. In this way, although the direct current holding circuits numbers three and four for the stop relay S^a and the control relay K^a are broken by the raising of the shoe 31, current is simultaneously supplied to said relays S^a and K^a by reason of the fact that the alternating current relays S^a and K^a are energized and their respective armatures 63 and 67 are raised to close the circuits numbers five and six for energizing

95 said relays S^a and K^a ; and this condition exists until the first pair of wheels 24—24 enter the control section B.

When the first pair of wheels 24 enter the control section B the coil 15 of the ramp

100 relay L is energized by the following circuit:

Circuit number ten.

From the track rail 2 of the control section B, conductor 84, coil 15, conductors 85 and 86, armature 11 of the track relay 10 in its upper position, conductor 87, armature 19 of the ramp relay L in its neutral position, conductors 88, 89 and 90 to the secondary of the transformer 21, conductors 91, 110 92, 93 and 94 to the track rail 1 and thence through the wheels 24 and the axle 25 back to the track rail 2. The coil 16 of the ramp relay 11 is also supplied with current from the transformer 22¹ of the control section

115 D along a circuit as follows:

Circuit number eleven.

From the track rail 1, conductors 94¹ and 95¹, armature 13¹ of the track relay 10¹ in its upper position, conductor 96¹ to the secondary of the transformer 22¹, conductor 97¹, armature 14¹, conductors 98¹ and 99, coil 16, conductors 100, 92, 93 and 94 back to the

125 track rail 1.

The coils 15 and 16 of the ramp relay L are connected through two different transformers 21 and 22¹ respectively to the same source of alternating current, and the connections between said coils and said trans-

130

formers is such that the relative time of the rise and fall of current in said coils causes the armatures of said relay to be moved from their neutral position, as shown in the drawing, to the left. In other words, the phase relation of the fluxes in the two coils 15 and 16 of the ramp relay L is such as to cause the armatures of said relay to be moved to the left. This phase relation, as will be clearly understood by those skilled in the art of alternating current railway signaling, may be changed by changing the connections to the source of alternating current, that is, to the line wires 4 and 5. The object of this arrangement and the effect produced by changing the phase of the currents in the coils 15 and 16 of the ramp relay L will be set forth hereinafter. When the armature 18 of the ramp relay L is moved to the left, a stick circuit for the coil 15 of said ramp relay is established as follows:

Circuit number twelve.

From the track rail 2 of the control section B, conductor 84, coil 15, conductors 85 and 101, armature 18, conductors 102 and 90, secondary of the transformer 21, conductors 91, 92, 93 and 94 to the track rail 1, and thence by the wheels 24 and the axle 25 back to the track rail 2.

When the first wheels and axle of the train enter the block section C the track relay 10 of said block section is shunted, due to the comparatively low resistance of said wheels and axle, and the armatures of said track relay will drop. The dropping of the armature 11 of the track relay 10 interrupts the circuit number ten for energizing the coil 15, but the movement of the armature 18 of the ramp relay L has in the meantime set up the stick circuit number twelve, so that the coil 15 will continue to be energized. When the armature 17 of the ramp relay L is moved to the left a high difference of potential is established between the ramp R and the track rail 1 according to the following circuit:

Circuit number thirteen.

From the ramp R, conductor 103, armature 17 in its lefthand position, conductors 104 and 82, high voltage tap *h* of the secondary of the transformer 20, and conductor 83 to the track rail 1.

When the coil 15 of the ramp relay L has once been energized and the armatures of said ramp relay have been moved to the left, these armatures will remain in this position, so long as there is a pair of wheels and an axle on the control section B, or until the head end of the train enters the block section E, because of the stick circuit number twelve; and so long as the armature 17 remains in its lefthand position, a high difference of potential exists between the ramp R

and the track rail 1, because of the circuit number thirteen.

From the foregoing it can be seen that when the block sections C and E are unoccupied a train approaching the ramp R will first encounter a high difference of potential between that ramp and the track rail 1, then as the train enters the control section B the armatures of the ramp relay L will be actuated to establish another circuit for maintaining this high difference of potential until the entire train has passed from the control section B, notwithstanding the fact that the first part of the train enters the block section C and deenergizes the track relay 10. In this way the ramp R is maintained in the same electrical condition during the passage of the entire train.

For the next condition of traffic to be considered, assume that the train is in the block section A and is about to enter the control section B; that said train has had an unobstructed trackway over which to pass and has been traveling unrestrained by the speed control device K; and that while the block section C is unoccupied there is a train in the block section E. Under these conditions the presence of the train in the block section E deenergizes the track relay 10¹ of said block section and causes its armatures to assume their lower position. The track relay 10¹ of the block section C, however, is energized and the partial circuit number nine hereinbefore set forth, which establishes a high difference of potential between the ramp R and the track rail 1 until the train first enters the control section B, will be set up in the same way as when the traffic conditions are such as assumed above. Also, the same circuit number ten for energizing the coil 15¹ of the ramp relay L will be set up. The dropping of the armature 13¹ and 14¹ of the track relay 10¹ changes the connections between the coil 16 of the ramp relay L and the secondary of the transformer 22¹ so that the phase relation between the current flowing in the coils 15 and 16 of said ramp relay L is different than under the conditions before assumed; and consequently, the armatures of the ramp relay L will move to the right instead of to the left. To explain further, assume that the polarity of the terminals of the secondary of the transformer 22¹ at a given instant is as indicated in the drawing and that the polarity of the terminals of the secondary of the transformer 21 at that instant is also as indicated. Then, with the parts in the position shown, the current will flow through either the circuit number ten or the circuit number twelve through the coil 15 from the conductor 85 to the conductor 84; and current will flow through the coil 16 upwardly from the conductor 100 to the conductor 99. On the contrary when the armatures 13¹ and 14¹ of the track relay 10¹

are in their lower position current will flow through the coil 16 in the opposite direction through the following circuit:

Circuit number fourteen.

From the terminal of the secondary of the transformer 22¹ assumed to be positive at a given instant, conductor 96¹, armature 13¹ in its lower position, conductor 107¹, conductor 99, coil 16, conductors 100, 92, 93 and 94 to the track rail 1, conductors 94¹, 98¹ and 106¹, armature 14¹ in its lower position, conductor 97¹ back to the other terminal of the transformer 22¹.

15 The reversal of the direction of flow of the current through the coil 16 as compared with the direction of the flow of current in the coil 15 at any given instant causes the armatures of the ramp relay L to be moved to their right, as shown in the drawing, and the stick circuit for the coil 15 of said relay is as follows:

Circuit number fifteen.

25 From the track rail 2, conductor 84, coil 15, conductor 85, conductor 101, armature 18 in its righthand position, conductors 109, 89 and 90 to the secondary of the transformer 21, conductors 91, 92, 93 and 94 to the track rail 1 and thence from the wheels 24 and the axle 25 back to the track rail 2.

The movement of the armature 17 of the ramp relay L to the right causes a low difference of potential between the ramp R 35 and the track rail 1 to be established according to the following circuit:

Circuit number sixteen.

From the ramp R, conductor 103, armature 17 in its righthand position, conductor 110, the low voltage tap σ of the secondary of the transformer 20, and conductor 83 to the track rail 1.

Since the shoe 31 is in electrical contact 45 with the ramp R at this time the low difference of potential sends current through the partial circuits numbers seven and eight for the alternating current relays S^a and K^a. The alternating current stop relay S^a is so 50 constructed that a low difference of potential between the shoe 31 and the frame of the train will send sufficient current through it to hold its armature 63 in its upper position; whereas the alternating current control relay K^a is so constructed that this low 55 difference of potential will not hold its armature 67 in its upper position. The operating characteristic of these relays S^a and K^a, whereby they are responsive to different 60 voltages, may be obtained in different ways, as will be appreciated by those skilled in the art of railway signaling; and for the purpose of understanding this invention it is deemed unnecessary to show and describe 65 the construction of these alternating current

relays S^a and K^a. When a low difference of potential exists between the ramp R and the track rail 1 the stop relay S^a is energized, since the armature 63 of its controlling relay S^a is raised; but the control relay K^a is deenergized, since the direct current holding circuit for said relay K^a number four is interrupted at the shoe and the armature 67 of its controlling relay K^a is dropped, as explained hereinbefore. Since the control 75 relay K^a is deenergized, its armature 45 drops and makes a break in the direct current holding circuit number four of said relay, so that after the shoe 31 has left engagement with the ramp and the contact 80 spring 34 has again made contact with the contact number 35, nevertheless this direct current holding circuit number four will be interrupted at the armature 45 and the control relay K^a will remain deenergized until 85 the next ramp is reached. When the armature 46 of the control relay K^a drops, it interrupts the normally closed circuit number two for the control device K; and sets the control device K into operation.

From the foregoing it can be seen that when the block section E is occupied by a train, the train when it passes the ramp R will have the control device K deenergized and set into operation, but the stop device S 95 will remain energized and will be incapable of affecting the movement of the train.

For the next traffic condition to be considered, assume that the train under consideration is in the block section A and about 100 to enter the control section B, as shown in the drawing; and that there is a train in the block section C. The presence of the train in the block section C deenergizes the track relay 10 and causes its armatures to 105 drop, and the dropping of the armature 12 of said track relay 10 interrupts the circuit number nine by which a high difference of potential is established between the ramp R and the track rail 1 before the train enters 110 the control section B. Also since the train has not yet entered the control section B the coil 15 of the ramp relay L is not energized and the armatures of said ramp relay are in their neutral position, as shown in the 115 drawing, in which the armature 17 opens a break in the circuits numbers thirteen and sixteen and prevents a high difference of potential from being established by the transformer 20¹ of the next control section 120 D. Consequently, as the shoe 31 of the train engages the ramp R, there will be no difference of potential between that ramp R and the track rail 1, and both the stop relay S^a and the control relay K^a will be deenergized, 125 because the raising of the shoe 31 interrupts the direct current holding circuits numbers three and four and the absence of any difference of potential between the ramp R and the track rail 1 prevents the alternating 130

current relays S^a and K^a from being energized. When the stop relay S^a is deenergized its armature 37 drops and interrupts the normally closed circuit number one for energizing the stop device S , thereby deenergizing said stop device and setting it into operation to bring the train to a stop.

Under ordinary conditions the presence of a train in the block section C would have set the control device K into operation when the train entered the block section A, in the same way as the presence of a train in the block section E causes the control device K to be set into operation as the train enters the block section C; and under these circumstances the train would be traveling under the dominance of the control device K at the time the stop device S is operated, with the result that the train is traveling at a low speed when its shoe engages the ramp R and will be immediately brought to a stop by the action of the device S . Under some special conditions, however, the dangerous condition existing in the block section C, which may be the presence of a train in said block section, or a broken rail in said block section, may arise after the train has entered the block section A, so that said train would be moving at speed when its shoe engages the ramp R and a stop device S is set into operation. Under these circumstances the brakes would be immediately applied to the train as it entered the control section B and if the dangerous condition in the block section C is near the end of said block section, the train may be brought to a stop before the point of danger is reached. If, however, the dangerous condition is located near the entrance to the block section C there is a possibility that the train may reach the point of danger; but it can be seen that for this to happen it is necessary that this dangerous condition should not exist when the train entered the block section A.

The ramps are of such length and are so located with reference to the insulating joint 3 at the entrance to each control section that the shoe 31 of the train will be in engagement with that ramp for a short distance before the first wheels and axle of the train enter the control section B. This distance is that required for the relays upon the train to operate, and will vary with different equipments. Another factor determining the length and location of the ramps is that the front end of the ramp should be located at such a distance from the insulating joint 3 at the entrance to each block section that the shoe 31 will not have left contact with the ramp before the first pair of wheels and axle of the train enter that block section.

The electrically operated devices along the track are shown as constructed to be operated by alternating current alone, and this is done in order to prevent stray direct cur-

rent from falsely operating the system; but it is to be understood that simple modifications, which will be apparent to those skilled in the art of railway signaling, may be made whereby direct current may be used as the controlling medium for the devices both on the train and along the trackway. Only one shoe 31 is shown, but any number of shoes and any number of cars may be included in the train without affecting the operation of the system, since the condition of the ramp is maintained the same while the entire length of the train is passing. It can be seen that this system is economical in line wire, only one wire 28 being required between adjacent block sections in addition to the regular line wires 4 and 5. While the transformers 20, 21 and 22 are shown as having both their primaries and secondaries distinct, it will be understood by those skilled in the art that these transformers may be combined into one with appropriate taps for obtaining the different voltages required. Other changes and modifications, apparent to those skilled in the art of railway signaling, may be made without altering or departing from the invention or the specific embodiment thereof shown and described.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In a system for automatically controlling railway trains, in combination: a trackway comprising electrically isolated block sections, a comparatively short control section at the entrance to each block section and electrically isolated therefrom, an insulated ramp disposed near the entrance to each of said block sections, high and low voltage sources of electrical energy associated with each ramp for creating high or low differences of potential between said ramp and the track rails, a three-position relay associated with each ramp, the energization of one of the coils of said relay being controlled by the presence of a train in the corresponding control section, the energization of the other coil of said relay being controlled by the presence of a train in the second succeeding block section, the polarity of said second mentioned coil of said relay relatively to the polarity of said first mentioned coil being reversed when a train occupies said second succeeding block, a circuit controller controlled by said three-position relay and connecting said high voltage source to said ramp when said relay is ac-

- 5 tuated to the position corresponding to the position to which it is actuated when said second succeeding block is not occupied, said circuit controller connecting said low voltage source to said ramp when operated to a position corresponding to the position to which it is operated when said second succeeding block section is occupied, and an automatic train control mechanism carried 10 by the train and responsive to said high and low differences of potential.
2. In a system for automatically controlling railway trains, in combination: a plurality of electrically isolated block sections, 15 an insulated ramp associated with each block section, a track relay and a source of electric current for the block section and constituting a normally closed track circuit therefor, high and low voltage sources of 20 electric current associated with each ramp for creating high or low differences of potential between said ramp and the track rails, a partial circuit controlled by the track relay of the next block section for establishing a high difference of potential between 25 said ramp and the track rails, a three-position relay associated with each ramp, the energization of one coil of said relay being controlled by the track relay of the next 30 block section, the energization of the other coil of said ramp relay being controlled by the track relay of the second succeeding block section, the polarity of said second mentioned coil relatively to said first mentioned coil being different according to whether or not said track relay of said second succeeding block is energized or de-energized, a partial circuit controlled by one position of said ramp relay for electrically connecting said ramp and said high voltage source, another partial circuit controlled by the other position of said ramp relay for electrically connecting said ramp and said low voltage source, and automatic 40 train control mechanism carried by the train and responsive to said high and low differences of potential.
3. In a system for automatically controlling railway trains, in combination: a track-way comprising electrically isolated block sections, a comparatively short control section at the entrance to each block section and electrically isolated therefrom, an insulated ramp disposed near the entrance to each of 45 said block sections, high and low voltage sources of electrical energy associated with each ramp for creating high or low differences of potential between said ramp and the track rails, a three-position relay associated with each ramp, the energization of one of the coils of said relay being controlled by the presence of a train in the corresponding control section, the energization of the other coil of said relay being 50 controlled by the presence of a train in the second succeeding block section, the polarity of said second mentioned coil of said relay relatively to the polarity of said first mentioned coil being reversed when a train occupies said second succeeding block, a 70 partial stick circuit for said coil of said three-position relay connected across the track rails of the corresponding control section, a circuit controller controlled by said three-position relay and connecting said high voltage source to said ramp when said relay is actuated to the position corresponding to the position to which it is actuated when said second succeeding block is not occupied, said circuit controller connecting said low voltage source to said ramp when operated to a position corresponding to the position to which it is operated when said second succeeding block section is occupied, and an automatic train control mechanism carried by 80 the train and responsive to said high and low differences of potential.
4. In a system for automatically controlling railway trains, in combination: a plurality of electrically isolated block sections, 85 a comparatively short control section at the entrance to each block section and electrically isolated therefrom, an insulated ramp associated with each block section, a track relay and a source of electric current 90 for the block section and constituting a normally closed track circuit therefor, high and low voltage sources of electric current associated with each ramp for creating high or low differences of potential between said ramp and the track rails, a partial circuit controlled by the track relay of the next block section for establishing a high difference of potential between said ramp and the track rails, a three-position relay associated 95 with each ramp, the energization of one coil of said relay being controlled by the track relay of the next block section, a partial stick circuit for said coil of said three-position relay connected across the track 100 rails of the corresponding control section, the energization of the other coil of said ramp relay being controlled by the track relay of the second succeeding block section, the polarity of said second mentioned coil relatively to said first mentioned coil being different according to whether or not said track relay of said second succeeding block is energized or de-energized, a partial circuit controlled by one position of said ramp relay for electrically connecting said ramp and said high voltage source, another partial circuit controlled by the other position of said ramp relay for electrically connecting said ramp and said low voltage source, and automatic 105 train control mechanism carried by the train and responsive to said high and low differences of potential.
5. In an automatic train control system, the combination with a railway track, of im- 110

10

- 5 pulse devices located at intervals along the track and adapted to assume different controlling conditions, sources of electrical energy for producing the different controlling 70 conditions of each impulse device, electromagnetic means normally disconnecting said sources from the corresponding impulse device, and traffic controlled means for controlling said electromagnetic means and selectively connecting said sources to the corresponding impulse device in accordance with the extent of unoccupied track in advance of that impulse device.

6. In an automatic train control system, 15 the combination with a railway track, of impulse devices located at intervals along the track and adapted to assume different controlling conditions, sources of current for producing the different controlling 80 conditions of each impulse device, a normally deenergized polarized relay having contact fingers which control selectively the connection between said sources and the corresponding impulse device when the relay is energized, 20 and traffic controlled means for determining the energization of each relay and the direction of movement of its contact fingers in accordance with the extent of unoccupied track 25 in advance of the corresponding impulse device.

7. In an automatic train control system, in combination: a track divided into blocks; a ramp associated with each block; partial circuits for determining the controlling 30 condition of each ramp; a normally deenergized polarized relay for controlling said partial circuits; means dependent on the presence of a train adjacent to said ramp and upon the corresponding block being unoccupied for 35 causing energization of said relay; and a circuit for each relay having its polarity dependent upon the presence or absence of a train in the block next in advance of the corresponding block.

8. In an automatic train control system, in combination: a track divided into blocks having track circuits; an impulse device associated with each block; circuits for determining the controlling condition of each impulse 40 device; a polarized relay for controlling said circuits; an energizing circuit for said relay controlled by the track circuit of the corresponding block; a maintaining circuit for said relay closed while a train is 45 passing the corresponding impulse device; and a circuit for each relay having its polarity controlled by the track circuit of the block next in advance of the corresponding block.

9. In an automatic train control system, 50 the combination with a track divided into blocks having track circuits; of an impulse device associated with each block and adapted to assume different controlling conditions, 55 controlling each impulse device, an energizing circuit for each relay controlled by the track circuit of the corresponding block, and a circuit for each relay having its polarity controlled by the track circuit of the block 70 next in advance of the corresponding block.

10. In an automatic train control system, 75 in combination: a track divided into blocks having track circuits; a comparatively short control section located at the entrance to each block and electrically isolated therefrom; an impulse device associated with each block; circuits for determining the controlling condition of each impulse device; a polarized relay for controlling said circuits; means controlled by the track circuit of the corresponding block for preventing the energization 80 of said relay when said block is occupied; a maintaining circuit for said relay dependent upon the preliminary energization 85 thereof and having its continuity established by a pair of wheels and axle on the corresponding control section; and a circuit for controlling each relay having its polarity controlled by the track circuit of the block 90 next in advance of the corresponding block.

11. In an automatic train control system, 95 the combination with a track divided into blocks; of an impulse device associated with each block for transmitting impulses of different controlling characteristics to a passing train, impulse transmitting circuits associated with each impulse device, a normally deenergized polarized relay having contact 100 fingers controlling said circuits, means for energizing said relay upon the approach of a train to each impulse device and for maintaining said relay energized while the train is passing that impulse device, means for preventing the operation of said means when the corresponding block is occupied, and means for determining the direction of movement of the contact fingers of each relay in the 105 block next in advance of the corresponding block.

12. In an automatic train control system, 110 the combination with a railway track, of impulse devices located at intervals along the track, a polyphase relay having two windings for governing the controlling condition of each impulse device, a circuit for one winding of said relay controlled by the presence of a pair of wheels and axle adjacent to the corresponding impulse device, and the circuit for the other winding of said relay having its polarity determined by traffic conditions for a predetermined distance 115 in advance of the corresponding impulse device.

13. In an automatic train control system, 120 the combination with a railroad track divided into blocks having track circuits, of a comparatively short control section at the entrance to each block and electrically iso- 125

- lated therefrom, an impulse device associated with each block, normally open circuits for governing the controlling condition of each impulse device, normally deenergized electromagnetic means for selectively controlling the continuity of said circuits, means controlled by the track circuit of the block next in advance for governing said electromagnetic means to determine the circuit controlled thereby, and a circuit associated with each electromagnetic means and controlled by the track circuit of the corresponding block for determining the energization thereof.
15. 14. In an automatic train control system, the combination with a railroad track divided into blocks having track circuits, of an impulse device associated with each block, normally open circuits for energizing each impulse device to cause it to assume different controlling conditions, a normally deenergized three-position relay for selectively controlling said circuits, means tending to cause energization of each relay and to maintain such energization while a train is passing the corresponding impulse device, said means being controlled by the track circuit of the corresponding block and being effective only when that block is not occupied, and means controlled by the track circuit of the block next in advance for determining the position assumed by the moving elements of each relay upon its energization.
15. In an automatic train control system, the combination with a railway track, having track circuits, of impulse devices located at intervals along the track, circuits for determining the controlling condition of each impulse device, and a normally deenergized polarized relay having contact fingers controlling said circuits and having its energization controlled by adjacent track circuits.
16. In an automatic train control system, the combination with a track divided into blocks having track circuits; of an impulse device located adjacent to the entrance end of each block, controlling circuits for each impulse device including sources of current of different electrical characteristics, a normally deenergized polarized relay for controlling said circuits, a circuit for each relay, means tending to cause energization of each relay upon passage of a train, and a pole-changing device included in each last mentioned circuit and controlled by the track circuit of the block next in advance of the corresponding block.
17. In an automatic train control system, the combination with a track divided into blocks having track circuits, of partial circuits associated with each block for transmitting electrical impulses to a passing train, a normally deenergized polarized relay for controlling said partial circuits, means controlled by the track circuit of the corresponding block for determining the energization of each relay, and a circuit for each relay having its polarity determined by the track circuit of the block next in advance of the corresponding block.

RICHARD C. LEAKE.
